LAMP STRUCTURE

Benjamin L. Levinson, New York, and Jack Korshin, Cedarhurst, N. Y., assignors to Levinson Manufacturing Co., Incorporated, Pawcatuck, Conn., a corporation of Connecticut

Application August 26, 1949, Serial No. 112,534

4 Claims. (Cl. 240—1)

1

The present invention relates to a lamp structure and in particular to one capable of use as a night light. In its more specific form the invention also relates to a lamp which is capable of being energized by a conventional A. C. power source and which is also capable of being energized by a battery source and utilized as a portable lamp of the flashlight type.

There is a need for a convenient attractive lamp of relatively low illuminating power, this type of lamp being utilized as a night light by those who desire to have some illumination in the room throughout the night, as a corridor guide, and the like. Battery-energized lamps of various types have been utilized for this purpose but they suffer from the drawback that the batteries which they carry are soon exhausted and require replacement. When a readily available and practically inexhaustible external supply of electric energy is available, as is the case in most homes, a lamp of the type which can be plugged into the electric source is much preferable because of the fact that it is useable substantially indefinitely, subject only to the burning out of the bulb, without having to depend upon or replace expendable batteries. Such plug-in type lamps suffer from the disadvantage that, in the event that the power source should fail, they are useless. Moreover, they cannot be moved about with any great facility and their location is dependent upon the location of the power source outlets to which they are connected. Because of the first drawback of these plug-in type lamps, a flashlight or other battery-energized lamp must still be owned by an individual to provide illumination when the power source fails. Because of the second drawback of the plug-in type lamps, an individual usually finds it desirable to own a separate flashlight in order to provide illumination in inaccessible corners or off the premises.

A plug-in type lamp placed by the bedside of a child or other individual who, for various psychological reasons, requires light during the night, will usually adequately illuminate the bedroom but if, for some reason, the individual in question is forced to leave the bedroom during the night, he cannot take the lamp with him and consequently the darkness of the unilluminated parts of the house will still constitute a mental and perhaps even a physical hazard. One way to overcome this difficulty is to provide a plurality of plug-in lamps throughout the house, but this expedient is uneconomical and wasteful and, moreover, requires a large initial monetary outlay.

The present invention provides for a lamp

which eliminates all of the above disadvantages since it is useable at will either as a plug-in lamp or as a portable, battery-operated lamp. To this end, the lamp structure is made in two parts, 5 a base adapted to be plugged into a power outlet and a lamp body securable to and separable from the base, the body preferably carrying a second source of electric power, usually in the form of a battery, so that the bulb in the lamp can be 10 energized and illuminated by the battery when the lamp body is separated from the base. When the lamp body is secured to the base, the bulb is electrically connected to the base in an appropriate manner so that the bulb may be energized 15 and illuminated by the external power source. Since the lamp body, when it is separated from the base, is entirely self-contained insofar as a power source and electrical connections are concerned, it may be illuminated independently of 20 failure of the external power source, may be utilized as a flashlight for illuminating out of the way corners and places outside the premises, and may be carried from the bedside through the house whenever that is desired. Nevertheless, 25 when the lamp body is connected to the base, it is so designed as to blend therewith and give the impression of a unitary and decorative lamp structure of relatively conventional type. Hence, there is provided a lamp of conventional appearance which may be plugged into an external 30 power source and illuminated thereby, thus functioning in all respects as efficiently as any other plug-in type lamp, and which may also be used, either temporarily or semi-permanently, in locations where plugging is not feasible, thus functioning in all respects as efficiently as a conventional flashlight or battery-energized lamp.

External power sources of the type generally available in homes provide 110 volts of electric potential. Any practical battery combination 40 will not generate a voltage even approximately near 110 volts. A bulb which will operate at 110 volts will hardly operate at the normal flashlight battery voltage of approximately 3 volts, and a bulb capable of operation at 3 volts will almost 45 immediately burn out if subjected to 110 volts. A difficulty is thus presented in designing a lamp which is capable of alternate energization by a 110 volt source or a 3 volt source. In order to solve this problem, the electrical connections between the external source of power and the bulb in the lamp structure of the present invention, which bulb is designed for energization at 3 volts 50 so that it may be efficiently illuminated by a battery source contained within the lamp body, includes a step-down transformer which will re-

duce the 110 volts of the conventional external source to a 3 volt value suitable for the bulb. It has been found most convenient to utilize this step-down transformer as the means for separately connecting the bulb and the external power source, thus eliminating the necessity for awkward plugs and sockets. One portion of the step-down transformer is contained within the lamp base, this portion being hereafter termed the primary, and the other portion, hereafter termed the secondary, is a part of the lamp body, the primary and secondary being so arranged on the base and body, respectively, that when the body is secured to the base the secondary is positioned adjacent to and in inductive relation to the primary. This mode of electrical interconnection, coupled with the spatial relationships between the primary and secondary and their positions on the base and body respectively, form an important part of the present invention independent of the provision of a second source of power. Even if a second source of power were not provided, this mode of connection permits the attainment, in a simple manner, of a desired low degree of illumination from a relatively high voltage source and in addition permits the replacement of a part of the lamp structure in a very simple manner. This replacement may be desired in order to provide a lamp of a different color scheme to go with a changed scheme of decoration or to substitute an undamaged for a damaged lamp body.

To the accomplishment of the foregoing objects and such other objects as may hereinafter appear, the present invention relates to a lamp structure as defined in the appended claims and as defined in this specification, taken together with the accompanying drawings, in which—

Fig. 1 is a side elevational view of a lamp of the present invention showing the base secured to the body;

Fig. 2 is a side cross-sectional view taken along the line 2—2 of Fig. 1 showing the lamp body independently of the lamp base;

Fig. 3 is a side cross-sectional view similar to Fig. 2 but showing the lamp base independently of the lamp body;

Fig. 4 is a side cross-sectional view similar to Figs. 2 and 3 but showing the lower part of the lamp with the base secured to the body;

Fig. 5 is a schematic circuit diagram showing the basic electrical elements involved in the energization of the bulb from an external power source;

Fig. 6 is a schematic circuit diagram showing one mode of electrical circuit connections, corresponding to those shown in Fig. 2, when the lamp body contains a second power source;

Figs. 7 and 8 are schematic circuit diagrams showing alternative methods of electrical connection; and

Fig. 9 is a side elevational view showing the lamp of the present invention in use not as a table lamp but as a reading lamp adapted to be secured to a headboard or the like.

The details of construction of the lamp of the present invention, and the design thereof, may be varied within extremely wide limits in manners well known to those skilled in the art of lamp manufacture when compared to the specific disclosure. The present invention is independent of the construction either of the lamp body or the lamp base except as hereinafter more particularly pointed out in the claims.

The lamp of the present invention comprises a

base generally designated A and a lamp body generally designated B. This body is here disclosed in flashlight-like form because that form is considered to be extremely well adapted to the present invention but, as has already been pointed out, the precise form either of the base A or the body B lends itself to great variation.

The base A comprises a structural portion 2 shown in Figs. 1 through 4 as a type which is adapted to be placed upon a table top or the like. The upper part of this portion 2 is provided with a recess 4 and in that recess the first circuit portion 6 is secured, that portion acting as the transformer primary and, as here disclosed, taking the shape of a coil supported upon the bottom 8 of the recess 4 and preferably centrally disposed therein, a considerable space 10 remaining in the recess 4 for a purpose hereinafter to be described. The base A is provided adjacent the recess 4 with a securing means, here shown as an externally threaded upstanding rim 12, adapted to cooperatively secure the lamp body B to the base A. The transformer primary or coil 6 is electrically connected to the wire 14 which extends out from the base A and which is adapted to be plugged into a suitable external power source in any conventional manner. A switch 16 is provided on the base A for connecting or disconnecting the transformer primary 6 to the external source of power and a pilot light 18 may be provided, if desired, to indicate when the transformer primary 6 is energized. Air passages 20 (see Fig. 3) may be provided in the bottom of the structural portion 2 of the base A in order to permit air circulation around the transformer primary 6, thus aiding in cooling the same. If desired, a bracket 22 may extend upwardly from the base A and may terminate in a dome-like reflector 24 to reflect and diffuse the light from the lamp.

The lamp body B comprises a casing 26 of any suitable material such as plastic, which casing is provided at its lower end with a securing means 28 in the form of an internally threaded depending flange cooperable with the externally threaded upstanding flange 12 of the base A in order to secure the body B to the base A. Depending from the body B and here disclosed as inside the depending flange 28 is a second circuit portion 30 which functions as a transformer secondary, this portion being here illustrated as a coil secured to and depending from an insulating plate 32 which is in turn secured to the body casing 26. This secondary coil 30 is so positioned on the body B that when the body B and base A are assembled, the secondary coil 30 will surround and be coaxial with the primary coil 6 and will be sufficiently close thereto so that it will be in inductive relation thereto, a transformer action thus taking place between the two coils 6 and 30.

Normal transformer construction calls for the placing of the primary and secondary as close to one another as is possible. In the lamp of the present invention, however, the necessity that the body B be readily removable from and replaceable on the base A requires that a considerable clearance be provided between the primary 6 and the secondary 30. This clearance is also required by the manufacturing tolerances in constructing the coils 6 and 30 and securing them to the structural portion 2 of the base A and to the insulating plate 32 on the body B respectively, it being essential that the various bases and lamp bodies be used interchangeably. The clearance is ex-

aggerated in the drawings for purposes of clarity. In order to provide for proper transformer action, despite the relatively large spacing between the primary 6 and the secondary 30, a magnetizable core 34 of iron or the like is secured to the bottom of the structural portion 2 of the base A inside, and preferably coaxial with, the primary coil 6. This core 34 concentrates the flux generated by the alternating current passing through the primary coil 6 and thus causes effective induction of a corresponding current in the secondary coil 30.

One possible mechanical construction for the lamp body B is disclosed in Figs. 1 and 2. A substantially cylindrical casing 26 is provided, the casing being apertured at 36 so that switch button 38 may project therethrough. One or more batteries 40 may be received within the casing 26, the batteries being here illustrated as of the flashlight type. The top of the casing 26 may be externally threaded as at 42 and a conductive plate 44 is adapted to be placed atop the casing 26, said plate 44 having a central aperture 46 through which the base 48 of a flashlight bulb 50 may be threaded so as to function as a socket for the bulb 50. The bulb base 48 acts as one terminal, the side terminal, for the bulb 50, the other bulb terminal being defined by its tip 66, all in conventional manner. A reflector 52 has a depending internally threaded flange 54 which cooperates with the externally threaded portion 42 of the casing 26, and ribs or ledges 56 on the interior of the reflector 52 act on the top surface of the plate 44 so as to retain that plate atop the casing 26.

The bottom of the casing 26 is defined by an open-ended housing 58 on the interior of which the plate 32 is secured and from which the securing means 28 depends. As here disclosed, the housing 58 is detachable from the casing 26 by means of the threaded engagement 60, but it could be made integral with the casing 26 if that be desired.

Secured to the plate 32 by means of rivet 62 is leaf spring 64 which tends to move upwardly and contact the underside of the lowermost battery 40, thus urging the battery 40 upwardly into engagement with the tip 66 of the bulb 50. A flexible lead 68 electrically connects the leaf spring 64 to a contact 70 positioned atop an upward protrusion 72 of the plate 32. A contact 74 is cooperable with the contact 70, the contact 74 being carried by arm 76 secured at one end to the plate 32 by means of rivet 78 and urged downwardly toward the plate 32 by means of spring 80. The arm 76 is of electrically conductive material and has secured thereto a depending pin 82, preferably of insulating material, which extends below the plate 32, projecting through the aperture 84 therein.

Various modes of electrical connection may be provided. Fig. 5 discloses in schematic form the basic electrical circuit, disregarding for the moment the batteries 40. Two transformer-coupled circuits are provided, one being defined by the wire 14 which is adapted to be plugged into any available source of alternating current, the switch 16, the pilot light 18 if desired, and the primary coil 6 which surrounds the magnetizable core 34. The second circuit is defined by the transformer secondary 30 one end of which is connected to the side terminal 48 of the bulb 50 and the other end of which is connected to the tip terminal 66 thereof. Consequently, it will be appreciated that whenever the wire 14 is connected to a source of alternating current and the switch 16 is closed, a

current will be induced in the secondary 30 which will in turn energize the bulb 50 and cause it to illuminate. Since, as has already been mentioned, the bulb 50 is of a type which is to be energized by flashlight batteries, it is incapable of withstanding the full 110 volts of the conventional alternating current source. Accordingly, the transformer defined by the primary 6 and the secondary 30 is of the step-down type, the ratio between the turns being such that 110 volts supplied to the primary coil 6 will induce a voltage of approximately 3 volts in the secondary coil 30.

Figs. 6, 7 and 8 disclose various modes of electrical connection in the lamp body B when a second electrical source, such as the batteries 40, is included therein. The schematic diagram of Fig. 6 corresponds to the connections disclosed in Fig. 2. One end of the secondary coil 30 is connected by means of lead 86, which passes through aperture 88 in the plate 32, to the side terminal 48 of the bulb 50, this preferably being accomplished mechanically by causing the end of the lead 86 to connect electrically with the conductive plate 44 into which the bulb 50 is screwed. The other end of the secondary coil 30 is connected by means of lead 90, which passes through aperture 92 in the plate 32, to contact point 94. A separated contact point 96 is connected by means of lead 98 to the tip terminal 66 of the bulb 50. Thus, whenever the contacts 94 and 96 are bridged, the bulb 50 will be electrically connected to the secondary coil 30.

The upper end of the battery 40 is electrically connected to the tip contact 66 of the bulb 50, this being indicated in Fig. 6 by the lead 100 but preferably being accomplished in the body B itself by direct physical contact as shown in Fig. 2. The other end of the battery 40 is electrically connected to the leaf spring 64 and from that spring, via the flexible lead 68, to the contact point 70. The cooperating contact 74 on the conductive arm 76 is electrically connected by means of lead 102 to contact point 104 and separated contact point 106 is electrically connected by lead 108 to the side terminal 48 of the bulb 50, which may be accomplished via conductive plate 44. Thus, whenever the contacts 104 and 106 are bridged, the bulb 50 will be electrically connected to and energized by the battery 40. The switch button 38 is movable to at least two positions, in one of which, illustrated in Fig. 6, the contacts 104 and 106 are bridged, the contacts 94 and 96 being disconnected, thus connecting the bulb 50 solely to the battery 40, and in another of which the contacts 94 and 96 are bridged, thus connecting the bulb 50 to the secondary coil 30, the contacts 104 and 106 being disconnected so as to disconnect the bulb from the battery 40. If desired, an intermediate position of the switch button 38 may be provided, in which neither of the contact pairs 94, 96 or 104, 106 are bridged, the bulb 50 then being disconnected from both sources of energization.

The switch structure defined by the arm 76, the contacts 70 and 74, and the plunger 82 is optional and it is provided in order to ensure that when the body B is secured to the base A the user of the lamp will not, by accident, keep the bulb 50 electrically connected to the battery 40 and thus deplete the battery while under the misapprehension that the bulb 50 is being energized by the external alternating current power source. Whenever the body B is removed from the base A, the spring 80 will pull the arm 76 downwardly, as illustrated in Fig. 2, until the contacts 72

and 74 engage, thus closing the circuit between them. When in this position placing the switch button 38 in the position illustrated in Fig. 6 will cause the bulb 50 to light, energized by the battery 40. When the contacts 72 and 74 are engaged, the plunger 82 will project downwardly an appreciable distance from the plate 32. When the body B is secured to the base A the depending tip of the plunger 82 will engage with a portion of the base A, here shown as the top of the magnetizable core 34, the plunger 82 thereby being raised so as to separate the contacts 70 and 74 (see Fig. 4). As a result, it will be impossible to illuminate the bulb 50 from the battery 40 when the body B is secured to the base A.

This circuit arrangement has the disadvantage that, should the external power source fail, the lamp cannot be illuminated except by separating the body B from the base A. The circuit diagram of Fig. 7 is similar to that of Fig. 6 but eliminates the contacts 70, 74 and their associated mechanism so that the lamp 50 may be illuminated by the battery 40 if the external power source should fail.

Fig. 8 discloses an alternative switching arrangement somewhat more automatic in operation than that of Fig. 6. In this arrangement, the arm 76, the position of which is controlled by the plunger 82 and the spring 80, not only controls the position of the contacts 70 and 74 but also, via mechanical connection 110, controls the relative position of contacts 112 and 114. Contact 112 is connected via lead 90' to one end of the secondary coil 30, the other end of that coil being connected as before, by means of lead 86, to the side terminal 48 of the bulb 50. The contact 114 is connected by means of lead 98' to the tip contact 66 of the bulb 50. Whenever the body B is secured to the base A the plunger 82 will be moved upwardly, thus lifting the arm 76 and separating the contacts 70 and 74 so as to automatically disconnect the bulb 50 from the battery 40. At the same time, the mechanical connection 110 will cause the contacts 112 and 114 to engage, thus automatically electrically connecting the bulb 50 to the secondary coil 30. Hence, whenever the body B is secured to the base A and the switch 16 in the base A is closed, the bulb 50 will be energized and illuminated by the external power source. As soon as the body B is separated from the base A, the spring 80 will move the arm 76 downwardly, thus separating the contacts 112 and 114 and disconnecting the bulb 50 from the secondary coil 30. At the same time the contacts 70 and 74 will engage, thus automatically connecting the bulb 50 to the battery 40 and causing automatic energization and illumination of the bulb 50 by the battery 40. If desired, a make and break switch of conventional type may be employed corresponding to the contacts 104 and 106 so that, even when the body B is removed from the base A, the bulb 50 can be illuminated or not at will.

In Fig. 2 the electrical connections are illustrated more or less schematically and may take the form of wires, flexible metallic strips, or the like, all as well known in the art.

Fig. 9 illustrates another embodiment of the present invention in which the lamp base A is not of the table-supported type but is instead mounted on a ball and socket joint 116 which is carried by a clamp 118 adapted to be secured, by means of screw 120, to a bed headboard 122 or the like. In this embodiment the lamp is adapted

for use as a reading light or as a fixed search-light type illuminator and yet retains all of the advantages heretofore set forth. This is but exemplary of the many uses to which the lamp may be put and is indicative of the many shapes and designs which it may assume.

The lamp of the present invention has the basic advantage that it permits the use of low voltage bulbs with relatively high voltage alternating current sources by means of a step-down transformer circuit arrangement, that arrangement facilitating removal and replacement of the lamp body or the lamp base. The lamp of the present invention has the further important advantage, when the lamp body is of the type which carries within itself a second source of electric current such as the batteries 40, that it may be used in fixed position so as to be energized by the external power source but can be moved about, at which time it will be energized by the second power source carried within the lamp body B, the body B being removable from the base A for that purpose. The lamp is also rendered substantially independent of failure of the external power source, since the batteries 40 may be utilized for illumination whenever that event occurs. In addition, the lamp body B may be separated from the base A and used as a conventional flashlight or the like, thus providing in a single structure a stationary lamp having a unitary appearance and a portable flashlight. Thus, it will no longer be necessary for an individual to purchase both a stationary night light and a flashlight.

The present invention has been here disclosed structurally in but two forms, and a few exemplary circuit arrangements have been shown each having advantages and disadvantages when compared to the other. It will be apparent that the specific disclosure may be varied in many respects without departing from the spirit of the invention as defined in the following claims.

We claim:

1. A lamp comprising a base having a recess therein, an annular transformer primary coil in said recess but only partially filling the same, a body including a bulb, means for separably securing said body to said base, an annular transformer secondary coil depending from said body and positionable in said recess, the internal diameter of one of said coils being greater than the external diameter of the other of said coils and said coils being positioned substantially concentrically in inductive relation when said body is secured to said base, and an electrical connection in said body between said secondary coil and said bulb.

2. The lamp of claim 1, in which the voltage relationship between primary and secondary coils is of a step-down nature and on the order of magnitude of 110 to 3.

3. In the lamp of claim 1, a second source of electric power in said body having a voltage comparable to the voltage rating of said bulb, an electric circuit between said second source and said bulb, and a switch connected in said circuit and in the electrical connections between said secondary and said bulb effective to connect said bulb either to said second source or to said secondary.

4. In the lamp of claim 2, a second source of electrical power in said body having a voltage comparable to the voltage rating of said bulb, an electrical circuit between said second source and said bulb, and a switch connected in said

circuit and in the electrical connections between said secondary coil and said bulb effective to connect said bulb either to said second source or to said secondary coil, said switch having a portion cooperable with said base when said body is secured thereto and effective to move said switch to a position in which said bulb is connected to said second source.
